UNITED STATES PATENT OFFICE.

JOHN ZILLIOX, OF ORCHARD PARK, NEW YORK.

METHOD OF MAKING KEY BOLTS.

Application filed March 24, 1922. Serial No. 546,340.

To all whom it may concern:

Be it known that I, JOHN ZILLIOX, a citizen of the United States, residing at Orchard Park, in the county of Erie and State 5 of New York, have invented new and useful Improvements in Methods of Making Key Bolts, of which the following is a specification.

This invention relates to a method of 10 producing that type of bolts which are held in place by a key driven through a slot in the same and which are commonly known as key bolts.

One of the objects of this invention is to 15 provide a method for producing a bolt of this character in which the metal is so distributed that the strength of the same is increased and the strain upon the same when tightening the key is caused to bear upon the 20 body of the bolt in such manner that there is no tendency to tilt or deflect the body but instead exert a straight pull on the central part thereof and thus ensure the maximum service for the amount of metal employed in 25 the bolt.

Another object is to provide an improved 30 method of manufacturing such bolts whereby the same may be produced from a solid piece of metal more economically and expeditiously and by the use of fewer operations and tools than have been required heretofore.

In the accompanying drawings:

Figure 1 is a side elevation of a key bolt 35 made in accordance with my method and showing the same connecting two plates, the latter being shown in section. Figure 2 is a sectional elevation of the bolt in connection with a key which is shown in elevation. Figure 3 is a cross section of the bolt taken 40 on line 3—3, Fig. 2. Figure 4 is a side view of the bolt and key taken at right angles to Figs. 1 and 2.

Similar characters of reference indicate 45 corresponding parts in the several views. In its general structure, the bolt constructed in accordance with my method comprises a body or shank 10 which preferably has a cylindrical exterior and provided with a longitudinal slot 11 adapted to receive a key 50 12 for engaging one side of the part to which the bolt is applied, and an integral one piece head 13 arranged at the rear end of the body and adapted to engage with the opposite side of the part to which the bolt is 55 applied. As shown in the drawings, the

bolt is represented as coupling two metal plates 15, 16, the overlapping parts of which are provided with registering openings 17, 18, which receive the body or shank of the bolt and one of said plates being engaged 60 by the head of the bolt and the other by said key. The front end 19 of the body is preferably tapered, so as to form a drift or centering end which permits of more readily inserting the same into the openings 65 of the plates and aligning the latter.

The slot in the body is provided at its opposite sides with two parallel longitudinal walls 20, 20, and at its opposite end with front and rear transverse end walls. The 70 front end wall tapers rearwardly and has two concave curved faces 21, 21, which converge from the opposite sides of the body inwardly toward the center of the same and terminate at the apex between the same in 75 a blunt face 22 forming a seat for the adjacent longitudinal edge of the key 12. The rear end wall tapers forwardly and has two concave curved faces 23, 23 which converge from the opposite sides of the body inwardly 80 toward the center of the same and terminate at the apex thereof in a sharp edge 24 which extends at right angles to the direction of the slot.

Due to this formation of the front end 85 wall of the slot in the bolt, the blunt seat 22 forms a bearing for the key which is arranged in the center of the bolt so that the strain exerted upon the latter when tightening the key produces a pull on the bolt which 90 is distributed over the entire metal of the same and in a direction parallel with its axis, thereby preventing the bolt from being tilted or deflected laterally and bent out of shape which not only reduces its holding 95 efficiency but also renders the bolt unfit for most effective use until the same is again straightened.

By making the rear end wall of the slot in the bolt of forwardly-tapering form, the 100 strength of the bolt next to its head is materially increased, owing to the increased amount of metal at this place which serves to prevent the head from being pulled off under excessive strains.

Moreover, this construction of bolt is much 105 stronger and is not liable to stretch out of shape when in use, and owing to the head being in one piece and formed integrally with the body, leakage past the same cannot 110

occur when the same is used for connecting the plates of a tank or wall intended to confine a liquid.

This bolt is made by first producing a circular cut lengthwise in the body from one side thereof by means of a rotary milling cutter of any suitable construction, which cut extends beyond the center of the bolt body, and then producing a similar cut 10 therein from the opposite side of the bolt body, so that these cuts intersect each other within the body of the bolt, as indicated by the dotted lines 25, and produce the concave faces 21, 21 and 23, 23 of the front and rear 15 end walls of the key slot. After the slot has been thus formed, the apex of the front tapering end wall is removed to form the blunt seat 22 by means of a punch or broaching tool or any other approved manner.

20 This method of making the bolt is very simple and permits of producing the same rapidly and economically without the use of expensive equipment.

A key bolt thus constructed utilizes the 25 amount of metal therein to better advantage, inasmuch as the same is disposed where most needed and thus secures the maximum

strength. Bolts of this character are particularly desirable for temporarily fitting together work which is subsequently permanently connected by ordinary bolts or rivets, such as iron for buildings, plates for tanks and ships, and the like, in which case the key bolts can be quickly applied to and removed from the work. Obviously, however, these bolts may be used for permanent connecting means, if desired.

I claim as my invention:

The hereindescribed method of making key bolts which consists in first producing a circular cut lengthwise in the body of the bolt from one side of the same and then producing a similar cut therein from the opposite side thereof, so as to intersect the first mentioned cut and thereby forming a longitudinal slot in the body which is adapted to receive a key, which cuts produce front and rear end walls for said slot which taper toward each other from opposite sides of said body, and then removing the apex of 50 the front end wall to form a blunt seat thereon for said key.

JOHN ZILLIOX.
